UNITED STATES PATENT OFFICE

139,282

DESIGN FOR A TEXTILE FABRIC

Leon L. Frank, New York, N. Y.

Application September 16, 1944, Serial No. 115,330

Term of patent 3½ years

(Cl. D92—1)

To all whom it may concern:

Be it known that I, Leon L. Frank, a citizen of the United States of America, residing in New York city, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The dot and dash lines on the drawing show the design unit, which unit is repeated in staggered relation as indicated by the angles A and A'.

I claim:

The ornamental design for a textile fabric, substantially as shown and described.

LEON L. FRANK.
